C. C. SANDERS

GREENHOUSE BENCH

Filed April 23, 1923

INVENTOR
CAREW C. SANDERS
By Edward G. Longane
ATTY.

UNITED STATES PATENT OFFICE.

CAREW C. SANDERS, OF ST. LOUIS, MISSOURI.

GREENHOUSE BENCH.

Application filed April 23, 1923. Serial No. 634,056.

To all whom it may concern:

Be it known that I, CAREW C. SANDERS, a citizen of the United States, and resident of the city of St. Louis, and State of Missouri, have invented certain new and useful Improvements in Greenhouse Benches, of which the following is a specification containing a full, clear, and exact description, reference being had to the accompanying drawings, 10 forming a part thereof.

My invention relates to improvements in greenhouse benches and has for its primary object a greenhouse bench, the legs of which are provided with roller supports for the 15 steam pipes so that the expansion and contraction of the pipes can be readily taken care of without the danger of breaking the connection.

A further object is to construct a greenhouse bench, the legs of which are formed 20 preferably from cement or concrete, and in which the sides of the bench are braced in a cheap and effective manner against bulging when the bench is filled with earth.

25 In the drawings:

Fig. 1 is a side elevation of a portion of the bench embodying my invention;

Fig. 2 is a cross section of the same;

30 Fig. 3 is an enlarged fragmental section showing the manner of bracing the sides;

Fig. 4 is an enlarged fragmental section showing the manner of supporting the steam pipes, and

35 Fig. 5 is an enlarged fragmental view of the upper end of one of the legs.

In the construction of my device I employ a plurality of legs or supports 6. These supports are preferably made of concrete or cement. The supports have extending 40 entirely therethrough, tubes or pipes 7, these acting as bearings or sockets for the supporting rods 8. The sockets 7 are spaced apart vertically, as illustrated in Fig. 1, the purpose of which will be explained in detail later. While the supports 8 may be either tubular as shown in Fig. 4 or they 45 may be solid cylindrical bars, the tubes however, are preferable. The legs 6 are provided on their lower ends with bases 9, which are enlarged so as to give the leg a firm foundation, and the upper ends of the legs are provided with grooves 10 in which sleepers 11 are located. Resting on the sleepers 11 are cross bars 12, which support the bed 13 50 of the bench. Secured along the edges and

ends of the bench are boards 14 which act as sides, and when in position, form a box open on its top for the reception of earth. The sides and ends 14 are braced by means of cleats 15 which are secured to the inside 60 of the sides 14 and to the outside of the sleeper 11 by any suitable fastening means, such as nails. The purpose of these cleats is to prevent the sides from bulging when the bench is filled with earth. In this connection, it will be noted from Fig. 3 that the boards forming the bottom of the bench adjacent the sides 14 are provided with cut away portions 16 so as to permit the cleat to pass therethrough. 65

Resting on the supports 8 is a heating coil 17. This heating coil is preferably heated by steam, although hot water may be used.

The purpose of the recess 10 is to prevent the legs 6 from shifting laterally as well as 70 to prevent any tendency of the bench from shifting on the legs. This of course is only liable to happen before the bench is loaded with earth, since the weight of the earth in the bench would naturally obviate this tendency. 75

In most greenhouses, the floor thereof is lower at one end than the other so as to provide drainage and where this is the case, the supports 8 may be inserted, as illustrated in 80 Fig. 1, or in other words, in the same row of sockets for the full length of the bench, the inclination of the floor providing the proper drainage for condensation in the pipes. Where the floor is level, however, the 85 supports are gradually lowered by placing them in different sockets so that the pipes 17 can drain and prevent the accumulation of condensation. If found desirable, the legs 6 may be formed of other material than 90 cement and provided with sockets and thus accomplish my purpose. 95

By providing a roller support for the steam pipes, breakage is obviated, because I have found, by practical experience, that in 100 installing steam pipes in greenhouses and supporting same so that they are not free to move longitudinally and take care of the expansion and contraction due to variation in temperature, a great deal of expense was involved in keeping the heating plant in repair, on account of the breakage of joints and elbows. By the use of my improvement, expansion and contraction is readily 105 taken care of and no breakage results due 110

to undue strain set up on the heating coils through expansion and contraction, as would be the case where the pipes are secured in hangers or rest on non-rotating supports.

5 By use of the cleats 15 I am enabled to keep the floor of the greenhouse clean and prevent any spilling of the earth due to the bulging of the sides.

I am aware that iron brackets have been 10 used to prevent the bulging of the sides, but this is expensive and furthermore, makes it extremely hard to tear down a bench, because these brackets must be secured by means of screws which rust through contact 15 with the damp earth and thus render it practically impossible to remove them. The brackets also rust and break when attempting to pry them loose. With my improvement the cost is so small that the cleats can 20 be thrown away with the remainder of the lumber used in the construction of the bench when it is necessary to renew the same.

The legs or supports 6 are preferably 25 monolithic structures and have the bases 9 sufficiently large so that they will stand solidly and thus obviate the necessity of tie rods. It is of course, essential that the legs on the opposite sides of the benches be lined up so that the supports 8 can fit in the bearings 30 7 and rotate freely therein. If an extremely wide bench is to be built, an extra row of supports and an extra sleeper 11 is extended along the center of the bench so as to 35 form a central support.

35 By my construction a greenhouse bench can be very readily assembled or taken down and no complicated system of pipe fitting or adjustment of tie rods, etc., is necessary. The roller supports 8 can also be readily replaced 40 when necessary by merely jacking up the heating coil 17 adjacent the roller supports to be replaced, after which the support can be readily slipped out of the leg and a new one inserted.

45 It is also possible to oil the supports or rather the ends which rest in the bearings 7. This oiling not alone permits the roller supports to turn readily, but will also assist in preventing them from rusting due to any 50 moisture which may creep from the bench along the leg. If found desirable, the

grooves 10 may be omitted and the top of the leg left flat.

By my construction benches of any length or width can be readily built and require 55 only the use of a hammer and saw, and no extra labor is required as is the case where pipe frames are used to support the bench.

I may also if desired, use a short pipe or 60 rod for the roller support and allow it to project on both sides of the leg, and when arranging the heating coils, position them so that they will be located on each side of the leg. In this way I am enabled to 65 reduce the length of the roller supports and thus cheapen the construction and at the same time accomplish all of the purposes of my invention.

Having fully described my invention what 70 I claim is:—

1. A greenhouse bench comprising a plurality of monolithic legs, bearings molded in said legs, a bench supported by said legs, roller supports mounted in some of said 75 bearings and extending laterally under said bench, and a heating coil supported on the roller supports.

2. A greenhouse bench comprising a plurality of monolithic legs, a bed carried by said legs, vertically spaced apart bearings, moulded in said legs, roller supports carried by certain of said bearings, and a heating coil carried by said roller supports. 80

3. A greenhouse bench comprising a plurality of monolithic legs each having an enlarged base and a grooved upper end, a bench resting in said grooves, bearings vertically spaced apart extending through and moulded in said legs, roller supports extending laterally below said bench carried by 85 some of said bearings, and a heating coil supported on said roller supports.

4. A greenhouse bench comprising a plurality of concrete legs, a bench carried by said legs, vertically spaced apart bearings moulded in said legs, roller supports located in some of said bearings, and a heating coil resting on said roller supports. 90 95

In testimony whereof I have signed my name to this specification.

CAREW C. SANDERS.
